METHOD OF PRINTING

George Rogers Brodie, Lower Merion Township, Montgomery County, Pa., assignor to Fred'k H. Levey Co., Inc., New York, N. Y., a corporation of New York

Application April 2, 1946, Serial No. 658,953

5 Claims. (Cl. 101—426)

1

This invention relates to a method of printing and particularly to an improved procedure in printing successively on opposite sides of a web or sheet, avoiding offsetting of the first impression when the second impression is made. Heretofore, various methods of accomplishing the desired result have been developed, the most widely used being the heating of the web or sheet after the impression has been made to rapidly dissipate the volatile solvent of the ink. Such procedure has been employed generally in the printing of magazines, the presses used for that purpose being so constructed as to permit the introduction of steam drums, radiant heaters or other heating units.

There are other types of printing presses, notably newspaper presses and roll-fed sheet delivery presses which, because of construction problems, cannot be fitted with heating means adapted to increase the temperature of the paper after the first or second impression.

It is the object of the present invention to provide an improved method of printing whereby the desired result of substantially instantaneous drying of each impression can be accomplished readily.

Other objects and advantages of the invention will be apparent as it is better understood by reference to the following specification and the accompanying drawing, which illustrates diagrammatically a printing press with means associated therewith to accomplish the purpose of the invention, it being understood that the illustration is not intended to limit the invention to presses of any particular type.

I have discovered that paper, preferably in the form of a web, may be heated effectively to temperatures ranging from about 225° F. upward to about 400° F., and that paper so heated may be printed with inks of the type embodying volatile solvents so that the solvents are evaporated substantially instantaneously when the impression is made and the impression is therefore immediately dry enough to permit second side printing without offset. The upper limit of 400° F. is merely indicative of a temperature above which many types of paper are likely to discolor or char. Obviously, the temperature must be kept below the point of discoloration. At the same time, sufficient heat must be retained in the paper to effect the evaporation of the solvent employed in the ink.

Heating of the paper may be accomplished in any suitable manner, for example by conveying it around a steam heated drum which is maintained at the temperature desired. In many cases it

2

may be desirable to surround the drum with a hood and to circulate heated air through the hood in order to bring the paper quickly to the desired temperature. The heating may be accomplished similarly by means of radiant heaters such as have been employed heretofore in the drying of printed impressions on paper webs and sheets. In order to attain the desired object, it is desirable also that the plate and impression cylinders of the press be cooled by a circulating medium such as water and maintained at a desirable temperature which may be atmospheric temperature or lower. The water, for example, may be maintained in a suitable tank and heated or cooled to the desired temperature by circulating a cooling or heating medium through a coil disposed in the tank. The water may be delivered to the press by a pump and returned to the tank.

Various types of inks may be employed. I prefer inks consisting of a pigment in a suitable vehicle comprising a resin and a solvent therefor having a vapor pressure such that the ink remains stable on the ink distributing system, the solvent being vaporized rapidly when the ink is subjected to elevated temperatures. Such inks are described in detail in the patent to Gessler No. 2,087,190. Such inks are well known in the art, and the following examples will serve to illustrate suitable formulations which, however, are subject to wide variations in so far as the application of the present invention is concerned.

Example I

Carbon black	17.0
Rosin modified with an alpha-beta unsaturated dicarboxylic acid	20.0
Propylene glycol	63.0
	100.0

Example II

Carbon black	17.0
Limed or zincated rosin	33.0
Non-aromatic petroleum fraction boiling from 441° to 516° F.	50.0
	100.0

When the web of paper has been heated, for example to approximately 300° F., in the manner hereinbefore described, it is conducted to the first plate and impression cylinders and receives the printed impression. The heat carried by the web is sufficient to immediately vaporize the solvent in the ink, leaving the dry impression. The web is conducted then immediately to the second plate and impression cylinders, where it is

printed on the reverse side. The heat still remaining in the paper is sufficient to vaporize the solvent, thus affording a dry second impression. Owing to the cooling of the plate and impression cylinders, the latter are not permitted to attain any dangerously high temperature, and the web is sufficiently cooled so that it may be cut into sheets in the usual manner and handled by the pressman.

While the invention will be described in more detail hereafter in a web perfecting press, it is equally applicable to roll fed sheet delivery presses in which the paper is heated while in web form and thereafter formed into sheets by guillotine cylinders, after which the sheets are conveyed by the usual mechanism commonly used for that purpose successively to the first and second plate and impression cylinders, so that the sheets are printed on both sides, the ink being dried substantially instantaneously by the heat carried in the paper.

Referring to the drawing, 5 and 6 indicate impression cylinders, and 7 and 8 plate cylinders which are mounted in the usual manner to rotate as the web 9 is fed over an idler 10, between the cylinders 5 and 7, over an idler 11, and thence between the cylinders 6 and 8 to receive the first and second side impressions. The plate cylinder 7 is supplied with ink through the usual rollers 12 forming a part of the ink feed system, and the plate cylinder 8 is similarly supplied with ink through the rollers 13.

The web is supplied from a mill roll 14 which is mounted for rotation and passes over idlers 15 and 16 to a heating drum 17 which is mounted for rotation and is adapted to be supplied with steam from any suitable source in order to maintain the periphery of the drum at the desired temperature. A housing 18 surrounds the drum 17 and is adapted to be supplied through an inlet 19 with a blast of air which may be heated in any suitable equipment and directed by a blower through the housing and about the periphery of the drum 17. The heated air escapes through an outlet 20. The web passes around an idler 21 and is directed to the idler 10.

The heating arrangement or some equivalent arrangement such as radiant burners is adapted to bring the temperature of the web to the point desired, which preferably is about 300°-325° F., although lower or higher temperatures may be used. At such temperatures the heat carried by the web to the plate cylinders is, as I have found, sufficient to dry the inked impression substantially instantaneously. Obviously the rate of drying will depend to some extent upon the nature of the solvents employed in the ink, and higher or lower temperatures in the web will be employed depending upon the vaporizing characteristics of the ink solvents. Likewise the speed of operation may vary, and lower temperatures may be employed at lower speeds.

The cooling of the plate and impression cylinders may be effected by providing a tank 22 in which a coil 23 is disposed to permit heating or cooling of the fluid such as water maintained in the tank. A pump 24 permits circulation of the cooling medium from the tank 22 through pipes 25 and 26 to the impression and plate cylinders 5, 6, 7 and 8. The cooling fluid returns through pipes 27 and 28 to the tank 22.

In accordance with the invention, effective drying of the inked impressions permitting second side printing without offset is accomplished in an economical and satisfactory manner. The

invention is particularly desirable in connection with types of presses in which it is not possible to install heating drums or other heating equipment in such a manner as to permit heating of the web or sheet after the first impression.

Various changes may be made in the structure and arrangement of the apparatus and in the procedure as described without departing from the invention or sacrificing the advantages thereof.

I claim:

1. The method of printing on sheet material in which the application of the ink thereon is by plate and impression cylinders which comprises heating the sheet material, applying to the heated sheet material the impression of an ink comprising a coloring agent and a vehicle containing a thickening agent and a solvent therefor having a sufficiently low vapor pressure to make the ink stable under normal press room printing conditions but capable of rapid vaporization solely by the application of heat, the heating of the sheet material prior to the application of the ink impression being to an elevated temperature below the point at which discoloration thereof usually occurs but to a temperature sufficiently high that the heat still carried by the sheet material at the time of the application of the ink impression thereto is sufficient to rapidly vaporize the solvent from the ink and leave a dry impression, and cooling the plate cylinder to prevent its overheating and the setting-up of the ink thereon.

2. The method of printing set forth in claim 1 in which the sheet material is heated prior to the application of the ink impression thereto to a temperature between 225° F. and 400° F.

3. The method of printing set forth in claim 1 in which the sheet material is heated prior to the application of the ink impression thereto to a temperature between 300° F. and 325° F.

4. The method of printing on sheet material in which the application of the ink thereon is by plate and impression cylinders which comprises maintaining the sheet material in heat-exchange relation with a heating means until it is heated to an elevated temperature, passing the heated sheet material from such heat-exchange relation to the heating means to a printing zone, applying to the heated sheet material at said printing zone the impression of an ink comprising a coloring agent and a vehicle containing a thickening agent and a solvent therefor having a sufficiently low vapor pressure to make the ink stable under normal press room printing conditions but capable of rapid vaporization solely by the application of heat, the elevated temperature to which the sheet material is heated while in heat-exchange relation with the heating means being below that at which discoloration of the sheet material would occur but sufficiently high that the heat still carried by the sheet material at the time of application of the ink impression thereto is sufficient to rapidly vaporize the solvent from the ink and leave a dry impression, and cooling the plate cylinder to prevent its overheating and the setting-up of the ink thereon.

5. The method of printing on sheet material in which the application of the ink thereon is by plate and impression cylinders which comprises heating the sheet material and applying to the heated sheet material the impression of an ink comprising a coloring agent and a vehicle containing a thickening agent and a solvent there-

for having a sufficiently low vapor pressure to make the ink stable under normal press room printing conditions but capable of rapid vaporization solely by the application of heat, and applying a similar ink impression on the reverse side of the sheet material, the heating of the sheet material prior to the application of the first ink impression thereto being to an elevated temperature below the point at which discoloration thereof normally occurs but to a temperature sufficiently high that the heat still carried by the sheet material at the time of application of the ink impression to the reverse side of the sheet material is sufficient to rapidly vaporize the solvent from the ink of said latter impression and leave 15 a dry impression, and cooling the plate cylinder to prevent its overheating and the setting-up of the ink thereon.
